UNITED STATES PATENT OFFICE.

GEORGE H. BRODERICK, OF LAWRENCE, KANSAS, ASSIGNOR TO IRVING HILL, OF LAWRENCE, KANSAS.

MACHINE FOR TAPING BOX-BLANKS AND THE LIKE.

1,270,924.

Specification of Letters Patent.

Patented July 2, 1918.

Application filed August 6, 1915. Serial No. 43,947.

To all whom it may concern:

Be it known that I, GEORGE H. BRODERICK, a citizen of the United States, and a resident of the city of Lawrence, county of Douglas, 5 and State of Kansas, have invented certain new and useful Improvements in Machines for Taping Box-Blanks and the like, of which the following is a specification.

This invention relates to improvements 10 in machines which are designed to perform or assist in the performance of a series of successive operations upon stock or material in substantially flat form. More specifically, this invention has in view facilitating the 15 operations of applying gummed or adhesive strips to the meeting edges of blanks or sheets of so-called paper board, particularly what is known as cellular or double-faced corrugated paper board, which has been so 20 slotted, scored and folded as to be readily formed into a box or carton when opened.

The present invention contemplates further improvements in a machine with which I am familiar and which includes a series 25 of counterbalancing weights, one weight of said series becoming effective, in a counterbalancing sense, as the weight of the accumulating material on a compressible portion of the table top overcomes the forces of 30 gravity of the counterbalancing weight theretofore effective, thus automatically maintaining a fixed positional relationship between the top blank of the increasing pile thereof and the mechanism for performing 35 the taping or other operation. In view of the fact that for the usual character of the material operated upon, about five blanks are required to overcome each effective counterbalancing weight, in turn, it will be 40 apparent that when the first of these five blanks is positioned, the forces tending to raise, or opposing downward movement of said compressible portion are substantially greater than when the fourth and fifth blank 45 are being positioned.

While it is essential to hold the top blank of the pile more or less firmly against the guides or supports in the taping and tape-cutting mechanisms, this force should not 50 be sufficient to crush or indent the material which, in the case of cellular or corrugated fiber board, is of a character which makes it somewhat pliable and yielding. Therefore, in the machine to which I have referred, the forces generated by each of the

counterbalancing weights, in turn, are slightly excessive when the first of each set of five blanks were operated upon, in order that said forces might still be sufficient to retain the compressible portion of the table 60 top at a proper point under the additional weight of the other four blanks of the set. The principal object of this invention is the provision of counterbalancing means for automatically retaining the compressible portion 65 of the table top in proper position under the proportionately increasing load of the increasing pile of blanks, which generate effective forces immediately upon the positioning of each blank, instead of when five 70 or more blanks have been positioned, thereby insuring the same pressure, of whatever desired degree, between each top blank, in turn, and the supporting and operating parts of the tape-cutting mechanism. The 75 invention also has in view the simplification of machines of this character, generally whereby the same may be wholly self-contained, and thereby readily movable from place to place in its entirety, may be manufactured and kept in repair at less cost, and is generally more dependable in operation.

My invention will be more readily understood by reference to the accompanying drawings, forming a part of this specification, in which—

Figure 1 is a perspective view of a machine embodying my invention;

Fig. 2 is an enlarged side elevation thereof, with one end broken away, and

Fig. 3 is an end elevation thereof.

Referring now to the drawings in detail, numeral 6 designates the top of a bench or table supported in the usual manner by the legs 7. This table-top 6 includes a compressible portion 8, which is of dimensions sufficient to receive and support a pile of blanks of any of the ordinary sizes. This compressible portion 8 is supported by a frame which includes the side bars 9 and 10 95 with the connecting bar 11 at one end thereof, the other ends of said side bars 9 and 10 being pivotally mounted upon the rod 12 which is carried by the arms 13 and 14 secured and depending from the fixed portion 6 of the table-top. The side bars 9 and 10 are pivotally connected to brackets 15 and 16, mounted upon the lower face of said compressible portion 8, whereby said compressible portion may be raised and lowered by oscil- 105 110

lation of its supporting frame and be retained in a substantially horizontal position, and to insure such position I provide vertical guides 17 17, in the form of angle bars, 5 which receive the corners of said depressible portion 8. To the cross bar 11 of the supporting frame is secured a cord 18, which passes around the sheave 19 and which is designed to support said frame and raise 10 and lower the same, and therewith said depressible table-top portion 8, in the manner hereinafter described.

Mounted upon the table-top 6 are the standards 20 and 20', journaled in the upper 15 ends of which is the shaft 21. Keyed to or otherwise suitably fixed upon this shaft 21 are the sheaves 22 and 23 and the cam-sheave 24. As these sheaves are designed to operate throughout less than one-half of one 20 revolution thereof, the sheaves 22 and 23 are of semi-circular configuration, and the cord 18, after being passed around the sheave 19, is directed through the groove in the periphery of the sheave 22 and the end thereof 25 suitably secured at the end 25 of said groove. At one end of the groove in the sheave 23 is secured a cord 26, carrying at its end the weight 27, and as said shaft 21 is rotated against the forces of gravity generated by 30 the weight 27, the cord 26 will be received in the sheave 23. The periphery of this sheave 23 being circular, the leverage will be constant for any position of said sheave, thereby making constant the forces generated 35 by the weight 27, as augmented by the leverage, which forces should counterbalance the weight of the depressible table-top portion by itself.

To one end of the groove in the cam-sheave 24 is similarly secured a cord 28 carrying the weight 29. The periphery of this cam-sheave 24 is of such configuration that when the depressible portion 8 of the table top is substantially flush with the fixed portion 40 thereof, the weight 29 hangs substantially directly below the axis of the shaft 21, which in this position, as shown in Fig. 3, it has obviously no effect upon said shaft. As the latter starts to rotate, however, under 45 action of the increasing load upon the depressible table-top portion 8 and consequent movement of the cord 18 around the sheave 22, not only will the forces of the weight 29 be deflected to oppose rotation of said shaft 50 21, but these forces will be constantly increased, as the shaft is rotated under the increasing weight of material placed upon the depressible table-top portion 8, through the constantly increasing leverage due to the 55 configuration of the portion 30 of the cam-sheave periphery.

Therefore, if the forces generated by the weight 27 are of a degree to counterbalance the weight of the depressible table-top portion 8 and its supporting frame, it will be

apparent that the weight 29 will commence to act, under a very slight leverage, as soon as any load is placed upon said depressible table-top portion, and that said leverage will vary in proportion to the increasing or diminishing weight of said load. Therefore, the upwardly-directed forces exerted against said depressible table-top portion 8, to press the topmost blank thereon against the taping and tape-cutting mechanism, will remain uniform irrespective of variations in the weight of the load.

The taping and tape-cutting mechanism, to which I have referred, in view of the fact that its specific construction and operation form no part of the present invention, need not be described in detail here. Generally speaking, it includes a suitable frame 31 carrying a reel 32 upon which the gummed tape is wound, the tape from said reel passing underneath the tension bar 32', over the moistening cylinder 33 and the scraper 34, and between the shearing knives 35 and 36 to the top blank 37' of the pile thereof on the depressible table-top portion 8. The lower knife 36 is fixed, and the upper knife 35 is pivoted to the frame 31 and is provided with an arm which has pivotal connection with the block 37.

To operate the knife 35, I provide the conveniently accessible foot-lever 38, to the rear end of which is secured the cord 39, which passes around the sheave 40 and is secured at its other end to the lever 40 fulcrumed in the standards 41. The other end 100 of the lever 40 is linked to the end of one arm of the bell crank lever 42, to the other arm of which is pivoted the connecting rod 43 operating through the arm 44 on the shaft 45 to rotate the latter and thus, 105 through the arm 46, raise the block 37 and operate the knife 35. A spring 47, in tension between the arm 43 and any suitably fixed part of either the table top 6 or the frame 31, retains the knife 35 normally in 110 its elevated position, and the lever 38 in position to be operated for the cutting operation, which, obviously, can be readily performed by the operator at any desired moment.

To retain each blank in a substantially flat condition during the taping and tape-cutting operations, tendencies to warp or become distorted through the inherent resiliency of the folded material and hold the meeting edges of the blank, to which the tape is applied, in proper position while the adhesive is "setting," I provide the bars 48 and 49 provided with the anti-friction rolls 50 and 51, respectively, at the ends thereof, 115 whereby a folded blank may be readily superposed on the pile thereof already taped, in proper position and condition to be operated upon. These bars may be supported in any desired manner. In the machine to 120

which I referred in the preamble of this specification, the lever 40 was supported from the ceiling of the room or mounted upon some support other than the table itself, whereas in the present invention it is mounted upon the table-top 6, thus making the entire machine more nearly self-contained and capable of ready removal from place to place without entire re-adjustment.

10 Many modifications of minor details of my improved machine for tapering box-blanks and the like will doubtless readily suggest themselves to those skilled in the art to which it appertains, and I therefore 15 do not desire to limit my invention to the specific construction herein shown and described.

I claim as new and desire to secure by Letters Patent:

20 1. In a machine of the character described, the combination, with a table or the like, of a balanced depressible section in the top thereof adapted to receive material thereon, and means for slightly and uniformly overbalancing an increasing or diminishing load on said section.

25 2. In a machine of the character described, the combination, with a table or the like, of a depressible section in the top thereof, 30 movable means for supporting said section in a counterbalanced condition, and means for slightly and uniformly overbalancing an increasing or diminishing load on said section.

35 3. In a machine of the character described, the combination, with a table or the like, of a balanced depressible section in the top thereof adapted to receive material thereon, means for guiding vertical movement of said 40 section and retaining the same in a horizontal position, and means for slightly and uniformly overbalancing an increasing or diminishing load on said section.

45 4. In a machine of the character described, the combination, with a table or the like, of a depressible section in the top thereof adapted to receive material thereon, means for supporting said section in a counterbalanced condition, means for guiding vertical 50 movement of said section and retaining the same in a horizontal position, and means for slightly and uniformly overbalancing an increasing or diminishing load on said section.

55 5. In a machine of the character described, the combination, with a table or the like, of a depressible section in the top thereof adapted to receive material thereon, a vertically 60 movable support for said section,

means for counterbalancing the weight of said section and its support, and means for 65 slightly and uniformly overbalancing an increasing or diminishing load on said section.

6. In a machine of the character described, the combination, with a table or the like, of a depressible section in the top thereof 65 adapted to receive material thereon, a vertically oscillating frame supporting said section, means for counterbalancing the weight of said section and its supporting frame, and means for slightly and uniformly overbalancing an increasing or diminishing load on said section.

7. In a machine of the character described, the combination, with a table or the like, of a depressible section in the top thereof 75 adapted to receive material thereon, a vertically movable support for said section, means for counterbalancing the weight of said section and its support, means for guiding vertical movement of said section and retaining same in a horizontal position, and means for slightly and uniformly overbalancing an increasing or diminishing load on said section.

8. In a machine of the character described, 80 the combination, with a table or the like, of a depressible section in the top thereof adapted to receive material thereon, a vertically oscillating frame supporting said section, means for counterbalancing the weight 85 of said section and its supporting frame, means for guiding vertical movement of said section and retaining same in a horizontal position, and means for slightly and uniformly overbalancing an increasing or 90 diminishing load on said section.

9. In a machine of the character described, the combination, with a table or the like, of a depressible section in the top adapted 100 to receive material thereon, a vertically oscillating support for said section may be held in a horizontal position in all positions thereof, means for guiding vertical movement of said section and retaining the same in a horizontal position, means for counterbalancing the weight of said section and its support, and means for slightly and uniformly overbalancing an increasing or 105 diminishing load on said section.

In testimony of the foregoing, I have hereunto set my hand in the presence of two witnesses.

GEORGE H. BRODERICK.
